FUNGICIDAL COMPOSITION

Bernhard Gaudian, 8 Ahrens St., Kitchener, Ontario, Canada, and Gunter Goeze, Köln-Bayenthal, Germany (% Fahlberg-List G.m.b.H. Chemische Fabrik, Gruner Platz 11, Postfach 140, Wolfenbuttel, Germany)
No Drawing. Filed July 27, 1959, Ser. No. 829,505
11 Claims. (Cl. 167—14)

This invention relates to improvements in the composition of fungicidal preparations effective in protecting plants against diseases such as Phytophthora, Fusidioidium, Cercospora, Peronospora and the like. More particularly it relates to improvements in fungicidal compositions in which the constituents imparting fungicidal properties are copper compounds supplemented by specific zinc compounds which produce a synergistic effect so that the resulting composition possesses fungicidal properties greatly in excess of those attributable to the use of similar amounts of copper compounds and zinc compound separately.

It is well known that protection against diseases of the groups listed above may be obtained by using copper compounds. When, however, this method is used the quantity of copper compounds necessary for an effective protection of fields of some acreage is prodigious. For instance, in actual practice it has been found that the amount of a copper compound necessary to keep a potato field free of Phytophthora, sprayed only once is between 2.5 and 5.0 kg. of cupric oxychloride or 1.2 and 2.4 kg. of cuprous oxide for an acreage of one hectare (2.417 acres).

It is well known that zinc compounds do not possess any noticeable fungicide properties in themselves. However, prior efforts to diminish the amount of copper compounds necessary to effectively protect the plants from diseases mentioned above have included proposals to use a combination of zinc or zinc compounds with copper compounds in order to produce effective parasiticides. One such proposal has been to dissolve copper and zinc salts in water and to produce by means of alkaline materials precipitates which are soluble to a small extent only. According to this proposition, a protective substance is formed which consists of a combination of basic copper and zinc sulphate. This composition, according to its author is said to have a synergistic effect and to produce a saving of copper up to 50%.

However various patents relating to this subject matter indicate that any such synergistic effect is not the general rule, but rather the exception, noted only with specific combinations of zinc and copper compounds, and not with most combinations.

For instance, in U.S. Patent 1,905,532 it is stated that soluble zinc compounds damage the foliage of solanaceous plants and the use of basic copper and zinc sulphate is proposed as a fungicide, hydrated lime being added to reduce the damage to the foliage. There is no mention of a synergistic effect and the mixture is proposed to prevent the damaging effect of zinc sulphate, per se, on the plants.

Another proposal is set forth in U.S. Patent 2,051,910 wherein the physical properties of copper silicate fungicides are said to be improved by replacing a portion of the copper with zinc. Lower damage to the foliage was noted without a noticeable impairment in toxicity.

In U.S. Patent 2,225,867 a specific synergistic effect is noted when zinc oxide is used in combination with copper oxide, which is not evident in the case of other compounds, according to the patentee. Indeed in other combinations, the patentee reported that the use of zinc compounds actually decreased the effectiveness of the product.

The patentee further notes that when other zinc compounds such as zinc carbonate, zinc silicate or zinc oxalate were used in place of zinc oxide, the results were merely additive and no synergistic effect could be found.

In still another U.S. Patent 2,540,209 it is stated that zinc sulfite is the only zinc salt which gives the desired protection against copper injury in copper fungicides, acting as buffering material.

In summary then, prior patents in this field would tend to indicate that it is by no means recognized that copper and zinc compounds in general, when used in combination, produce synergistic effects, and that one prevailing view is that a large number of zinc compounds can only be used if they can be converted to basic compounds.

According to the present invention a marked improvement in the effectiveness of fungicides copper compounds over the improvements previously reported is obtained by the use of zinc chromate and/or zinc sulphide, in admixture with fungicide copper compounds.

Specifically it has been found that the amount of copper compounds, such as cuprous oxide, copper oxychloride, basic copper carbonate, and the like may be reduced by as much as 75% when used with the proper proportions of the zinc compounds specified.

Thus in the prior art above noted, the best reported results amounted to a saving of 50% of copper when a combination of a basic copper-zinc sulphate is used, when compared with the action of a copper-sulphate-lime solution. However, we have found that with a suitable copper compound used in combination with zinc sulphide or zinc chromate, an unexpectedly high saving with respect to the copper compound is obtained and that only about one-fourth of the amount of copper compound heretofore deemed necessary need actually be used to effectively control the diseases mentioned.

For instance, if a copper sulphate solution with 0.75% of copper sulphate is used in order to keep potato fields free of Phytophthora, it is necessary, according to the accepted practice, to use about 600 liters for treating one hectare (2.417 acres) in order to treat the plants uniformly. It is therefore necessary to expend for each hectare, 4.5 kg. of copper sulphate, a figure which corresponds to 1.8 kg. of metallic copper.

However, if according to the invention a combination of for instance, copper oxychloride and zinc sulphide is used, actual field tests have proved that for each hectare only 600 g. of copper oxychloride must be used which contains 350 g. of metallic copper. This is clearly an effect which could not have been foreseen. The savings thus obtained are about four times the savings obtainable by the best method of saving so far mentioned in the literature above quoted. The savings are still greater if compared with those plant protection compounds and mixtures which are now used and which have been endorsed officially by Government authorities. One of these recognized spraying means containing copper, uses 2.5 kg. of copper oxychloride with a content of 1.45 kg. of copper metal for each hectare sprayed. This is the best compound now known which has found general recognition. Therefore, when compared with the most modern copper spraying fungicide the combination according to the invention has the advantage that it uses only one-fourth of the copper or, otherwise stated, that a quantity equal to three times the quantity actually used can be considered as having been saved.

A further advantage of the invention consists in the fact that the rather cumbersome conversion of the copper and zinc compounds into their basic salts by means of substances of alkaline reaction can be dispensed with.

A further advantage of the combination consists in the fact that no damage to the foliage results, even if the

dosage should for some reason or other be excessive. While applicants do not want to advance any theory for this increased effectiveness, they assume that zinc chromate as well as zinc sulphide activate the copper compounds to a high degree. This has been deduced from experiments with other zinc compounds (e.g. with zinc carbonate) which do not produce any increase in the effectiveness of the copper salts as a fungicide.

Before illustrating this invention in the specific examples which follow, certain limiting and critical features of the invention should be noted as follows:

(1) The only zinc compounds found to produce the pronounced improvement were zinc sulphide and zinc chromate.

(2) The copper fungicides to which the invention is applicable are those copper compounds which are insoluble or difficultly soluble in water. Specific members of this class include: cuprous oxide, copper oxychloride, copper hydroxide and basic copper carbonate.

(3) The amount of zinc compound to be used may vary considerably. It depends upon the nature of inert diluents in the mixture, and upon the plant to which the dust or spray is to be applied. The relative proportions of zinc compound: copper compound in the mixture should preferably be between 1:4 and 1:8; that is, for every five parts by weight of zinc compound, between 20 and 40 parts by weight of a suitable copper fungicide should be present.

(4) Other ingredients which may be present in the composition include diluents commonly used in the preparation of sprays, pastes or dusts.

The examples which follow are intended to be taken as illustrative of the invention and not as limitative.

Example 1.—Spraying Powder

[Proportions in grams]

25 g. copper oxychloride, and 5 g. zinc chromate are intimately mixed with 55 g. kaolin. In this mixture 5 g. of a higher molecular weight aliphatic sulfonic acid acting as a wetting agent and as an emulsifier such as sodium sulforicinate and 10 g. of an adhesive known as "cell powder" are worked.

A suspension of 3 kg. of a mixture, prepared with the above proportions indicated in grams, in 600 liters of water is prepared. This quantity is sprayed uniformly on each hectare of a potato field.

In an experimental test the potato plants on a ground parcel were treated and those on an adjacent ground parcel were not treated by spraying. On the non-treated section the plants on account of infestation with Phytophthora died, on the sprayed section the plants remained healthy and completely free of Phytophthora.

Example 2.—Spraying Paste

[Proportions in grams]

30 g. copper oxychloride and 5 g. zinc sulphide are stirred and intimately and thoroughly mixed by agitation with 25 g. of a watery dispersion of polyvinylacetate, 0.5 g. animal glue powder, the latter acting as a stabilizer, and 39.5 g. of water.

The mix has the consistency of a paste and 3 kg. of this paste are suspended in 600 liters of water. This quantity is sprayed on one hectare (2.417 acres) of potato plants.

The experiment mentioned in Example 1, was also made with this mixture of Example 2.

Example 3.—Spraying Paste

[Proportions in grams]

The same effect as that described in Examples 1 and 2 is obtained with a mix of 22 g. cuprous oxide, 5 g. zinc sulphide, 25 g. of a watery dispersion of polyvinyl propionate, 0.5 g. of animal glue serving as a stabilizer, and 47.5 g. of water which are intimately mixed to form a paste. 3 kg. of the paste suspended in 600 liters of water

are again the quantity sprayed for each hectare of a potato field.

Example 4.—Spraying Paste

[Proportions in grams]

5 30 g. copper oxychloride, 5 g. zinc sulphide, are mixed intimately and thoroughly with 25 g. of a water dispersion of polyvinylacetate, 0.5 g. of animal glue and 39.5 g. of water.

In order to prevent Peronospora on hops, the hops are sprayed with a 0.5% suspension of the paste in water.

Experimental tests similar to those described in Example 1 were made on two adjacent ground parcels planted with hops. The hops on one ground parcel was sprayed and the other left unsprayed. The hops in the untreated ground parcel were severely attacked by Peronospora while the hops which were sprayed did not show any Peronospora attack and remained healthy.

Example 5.—Spraying Paste

10 The spray prepared according to Example 4 was tested on beets attacked by Cercospora. A test was made exactly as described in Example 4 with the same results.

Example 6.—Spraying Powder

[Proportions in grams]

15 20 g. of copper oxychloride, 5 g. zinc sulphide are mixed with 60 g. kaolin. Into this mix 5 g. of a higher molecular weight aromatic sulfonic acid, acting as a wetting and dispersion agent and 10 g. of powder acting as an adhesive agent were worked, until complete homogeneity was obtained. A 0.30% suspension of this spraying powder in water was sprayed on apple trees during the pre-blossoming period to prevent infestation with Fuscipladium. The effect when compared with trees which had not been sprayed was very marked.

20 To this spray insecticides were added, especially gamma hexachlorocyclohexane and dichlordiphenyltrichlorethane.

Example 7.—Spraying Powder

[Proportions in grams]

25 30 g. cuprous oxide, 5 g. zinc sulphide are mixed with 45 g. of kaolin. Into this mix 5 g. of high molecular weight aliphatic sulfonic acid such as sodium sulforicinate and 10 g. of an adhesive known as "cell powder" and 5 g. hexachlorocyclohexane are worked.

30 2 kg. of this spraying powder are suspended in 600 liters of water and are sprayed over 1 hectare of ground with potato plants. Infection with Phytophthora was completely prevented. The Colorado potato beetle and its larvae were completely killed by the spraying.

Example 8.—Spray Powder

35 35 g. basic copper carbonate and 4 g. zinc sulphide are 40 mixed with 46 g. kaolin, 5 g. of a high molecular weight aliphatic sulfonic acid, as wetting and emulsifying agent, and 10 g. cellulose powder, as binding agent, are worked into the mixture.

40 3 kg. of the powder was dispersed in 600 liters of water and uniformly sprayed over one hectare of potato plants. Lots not sprayed developed a Phytophthora infection. The sprayed lots remained healthy and free of Phytophthora.

Example 9.—Spray Paste

45 30 g. basic copper carbonate and 5 g. zinc chromate are 50 stirred with 25 g. of an aqueous dispersion of polyvinyl acetate, 0.5 g. lime powder as stabilizer and 39.5 g. water.

50 3 kg. of this pasty mass was disposed in 600 liters of water and sprayed over one hectare of potato plants. The effectiveness against Phytophthora was the same as in Example 8.

Example 10.—Spray Powder

55 25 g. copper hydroxide and 5 g. zinc sulphide are mixed

with 55 g. kaolin, 5 g. of a high molecular weight aliphatic sulfonic acid, as wetting and emulsifying agent, and 10 g. cellulose powder, as binding agent, are worked into the mixture.

Field experimentation, employing 3-6 kg. of this spray powder dispersed in 600 liters of water as a spray over one hectare of beets, produced inhibition of infection by Cercospora.

Example 11.—Spray Paste

30 g. copper hydroxide and 5 g. zinc chromate are stirred with 25 g. of an aqueous dispersion of polyvinyl acetate, 0.5 g. lime powder as stabilizer and 39.5 g. water.

3 kg. of this pasty mass is dispersed in 600 liters of water and sprayed over one hectare of beets. The effectiveness against Cercospora was the same as in Example 10.

This application is a continuation-in-part of Serial No. 547,303, filed November 16, 1955, now abandoned in favor of the present application.

What is claimed as new is as follows:

1. A mixture for protecting plants against fungicidal diseases such as Phytophthora, Fusicladium, Cercospora, and Peronospora comprising for each 5 parts in weight of a zinc compound of the group consisting of zinc sulphide and zinc chromate, between 20 and 45 parts by weight of an insoluble fungicidal copper compound of the group consisting of cuprous oxide, copper hydroxide, copper oxychloride and basic copper carbonate; and from 3 to 12 parts by weight of kaolin.

2. A fungicidal mixture consisting essentially of 5 parts by weight of zinc chromate and 25 parts by weight of copper oxychloride.

3. A fungicidal mixture consisting essentially of between 20 and 40 parts by weight of copper oxychloride and about 5 parts by weight of zinc sulphide.

4. A fungicidal mixture consisting essentially of zinc sulphide and basic copper carbonate in the relative proportions of about 1 part of zinc sulfide to between 4 and 9 parts of basic copper carbonate, by weight.

10

15

20

25

30

40

5. A fungicidal mixture consisting essentially of zinc sulphide and copper hydroxide in the relative proportions of about 1 part of zinc sulfide to between about 4 and 9 parts of copper hydroxide, by weight.

6. The process of controlling fungus growth of a fungus selected from the group consisting of Phytophthora, Fusicladium, Cercospora, and Peronospora on living plants which comprises applying to the plant a fungicidal composition having as an active ingredient a mixture consisting of a zinc compound selected from the group consisting of zinc sulphide and zinc chromate and a copper compound selected from the group consisting of cuprous oxide, copper hydroxide, copper oxychloride and basic copper carbonate the relative proportions of said zinc compound and said copper compound being between about 4 and 9 parts by weight of copper compound for each part of weight of zinc compound.

7. The method of claim 6, wherein the mixture contains between 20 and 45 parts by weight of copper compound for each 5 parts by weight of zinc compound.

8. The method of claim 6 wherein the zinc compound is zinc chromate and the copper compound is copper oxychloride.

9. The method of claim 6 wherein the zinc compound is zinc sulphide and the copper compound is copper oxychloride.

10. The method of claim 6 wherein the zinc compound is zinc sulphide and the copper compound is basic copper carbonate.

11. The method of claim 6 wherein the zinc compound is zinc sulphide and the copper compound is copper hydroxide.
